CLAIM

The ornamental design for a snowmobile side fairing, as shown and described.

DESCRIPTION

FIG. 1 is a perspective view taken from a front, left side of a snowmobile side fairing according to an embodiment of our design;

FIG. 2 is a perspective view taken from a rear, left side thereof;

FIG. 3 is a left side elevation view thereof;

FIG. 4 is a front elevation view thereof;

FIG. 5 is a right side elevation view thereof;

FIG. 6 is a rear elevation view thereof;

FIG. 7 is a top plan view thereof;

FIG. 8 is a bottom plan view thereof;

FIG. 9 is a perspective view taken from a front, left side thereof shown on a snowmobile shown in dashed lines;

FIG. 10 is a perspective view taken from a front, right side of a snowmobile side fairing according to another embodiment of our design;

FIG. 11 is a perspective view taken from a rear, right side thereof;

FIG. 12 is a right side elevation view thereof;

FIG. 13 is a front elevation view thereof;

FIG. 14 is a left side elevation view thereof;

FIG. 15 is a rear elevation view thereof;

FIG. 16 is a top plan view thereof;

FIG. 17 is a bottom plan view thereof; and,

FIG. 18 is a perspective view taken from a front, right side thereof shown on the snowmobile shown in dashed lines.

Throughout the Figures, where shown: (i) the dashed lines showing additional structure of the snowmobile side fairing and portions of the snowmobile are for illustrative purposes

(Continued)

only and form no part of the claimed design; and (ii) the dotted/dashed lines illustrate unclaimed boundaries of surfaces claimed as part of the design. The invention includes mirror images of the embodiments of the snowmobile side fairing shown in the Figures.
